(57) **CLAIM**

The ornamental design for a case for electronic communications device, as shown and described.

DESCRIPTION

FIG. 1 is a front perspective view of a case for electronic communications device showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an enlarged detail view of the encircled portion in FIG. 3; the pattern shown in this enlarged detail is also, representative of the pattern at the bottom front of the case. The interior of the case, including all surfaces and features within the innermost of the solid peripheral object lines in each of FIGS. 2 and 4, forms no part of the claimed design. The dot-dash broken line circle in FIGS. 3 and 9 delineates a portion of the case for electronic communications device that is part of the claimed design and that is shown on an enlarged scale in FIG. 9. All other dot-dash broken lines represent the bounds of the claimed design. The dashed broken lines throughout the drawing figures depict portions of the case for electronic communications device that form no part of the claimed design. The broken lines form no part of the claimed design.
